UNITED STATES PATENT OFFICE

155,998

DESIGN FOR A COMBINED ASH TRAY AND HOLDER FOR MATCHES AND OTHER ARTICLES

Joseph Grzeca, Chicago, Ill.

Application August 7, 1947, Serial No. 140,753

Term of patent 3½ years

(Cl. D44—24)

To all whom it may concern:

Be it known that I, Joseph Grzeca, a citizen of the United States, residing at Chicago, Cook County, Illinois, have invented a new, original, and ornamental Design for a Combined Ash Tray and Holder for Matches and Other Articles, of which the following is a specification, reference being had to the accompanying drawing, forming a part thereof, wherein:

Fig. 1 is a top plan view of a combined ash tray and holder for matches and other articles, showing my new design;

Fig. 2 is a side elevational view;

Fig. 3 is an end elevational view;

Fig. 4 is another side elevational view; and

Fig. 5 is a bottom plan view thereof.

I claim:

The ornamental design for a combined ash tray and holder for matches and other articles, as shown.

JOSEPH GRZECa.
